NOVELTY LENS FOR SUNGLASSES

José Canato Filho, Caixa Postal, 706, 15100-Sao do Rio
Preto, Sao Paulo, Brazil

Filed Aug. 10, 1973, Ser. No. 387,273

Term of patent 14 years

Int. Cl. D16—06

U.S. Cl. D57—1 A

Fig. 1.

Fig. 2

Fig. 3

FIG. 1 is a front view of a novelty lens for sunglasses showing my new design;

FIG. 2 is a side view thereof; and

FIG. 3 is a front view thereof, the frame being shown in broken lines for illustrative purposes only.

The lens is shaded to indicate contrast.

I claim:

The ornamental design for a novelty lens for sunglasses, as shown and described.
